WALTER ROSENHAIN AND SYDNEY L. ARCHBUTT, OF TEDDINGTON, ENGLAND.

CONSTRUCTION OF AEROPLANE-WINGS OR OTHER LIKE STRUCTURES.

1,322,348.

Specification of Letters Patent. Patented Nov. 18, 1919.

Application filed July 22, 1919. Serial No. 312,593.

To all whom it may concern:

Be it known that we, WALTER ROSENHAIN, D. Sc., F. R. S., and SYDNEY LEONARD ARCHBUTT, F. I. C., both subjects of the King of Great Britain and Ireland, and both residing at the National Physical Laboratory, Teddington, in the county of Middlesex, England, have invented certain new and useful Improvements in the Construction of Aeroplane-Wings or other like Structures, of which the following is a specification.

This invention relates to the construction of aeroplane wings or other structures involving the employment of sheet metal or other material which cannot readily be tensioned by hand or by the application of a dope such as is usually employed for finally tensioning the fabric hitherto adopted for such structures.

20 The invention is principally intended to facilitate the employment of sheet metal, but it will be clear that it may be applied with equal effect and like advantage with fabric or with any other suitable flexible material.

It has hitherto been proposed in connection with the fastening of fabric upon structures to provide grooves upon the structure situated near the edges of the fabric, 30 so that the latter may be secured in the grooves by means of ropes, fillets or the like, and incidental to such securing of the fabric the latter is also tensioned.

For metal sheet, however, with which 35 this invention is principally concerned, such methods would be entirely unsuitable owing to the stiffness and rigidity of the metal with the consequent high tensile forces necessary to render the metal sheet sufficiently 40 smooth for practical purposes.

The present invention comprises a method of securing sheet metal or other material upon aeroplane wings or other like structures which consist in first stretching the 45 material as tightly as possible by hand or otherwise upon or around the structure, next securing the material in such position by suitable means, and finally further tensioning the material by the use of fillets adapted 50 to force the material into the grooves or depressions formed in the structure.

The accompanying drawings illustrate one mode of carrying out the invention.

Figure 1 is a sectional view showing one 55 form of wing constructed in accordance with the invention.

Fig. 2 is a fragmentary view on a larger scale.

In carrying our invention into effect in one convenient manner, as for example, in its application to the construction of an aeroplane wing, the latter may be formed somewhat in the usual manner with two main spars *a* having flanges *b* *c* at the top and bottom respectively, and around the framing of the wing the thin metal sheet *d* is initially stretched as tightly as is reasonably possible by hand or otherwise.

The flanged portions of the spars are formed with depressions or grooves preferably running longitudinally of the spars and into the four grooves thus formed fillets *e* are forced by bolts *f*, screws or other convenient devices or attachments so that the sheet metal will also thus be forced into the depressions and the final tensioning of the material will accordingly thereby be performed. The fillets may be made of wood or light alloy or other suitable material and are preferably so shaped that when forced home into position they will be substantially flush with and conform to the outer surface of the wing while the screws or other like attachments may be countersunk or otherwise suitably arranged so that there need be no appreciable projection of wire, nut or other device above the ring surface.

By such a method of construction the metal sheet can be readily tensioned to a satisfactory extent while there is no undue complication in the construction of the wing frame, and in fact it may be possible to simplify the construction by omitting some or all of the bracing wires at present employed owing to the material strengthening or stiffening of the wing as a whole by the frictional grip between the covering sheet and the flanges of the main spars. Moreover, by making the metal sheet of sufficient thickness it may be possible to utilize the covering itself to carry an appreciable part of the load of the wing, the whole wing in such case acting as a box girder of shallow section.

105 The sheet metal or other thin material may be of any desired width, but preferably of a width equal to the distance between the centers of adjacent ribs or slightly wider. The sheet metal may be used in lengths sufficient entirely to surround the wing frame in fore and aft directions, so that one

joint only would be required which could then be placed beneath one of the tightening fillets. Even in this case, when the fillets are screwed home or are sufficiently tightened, a frictional grip will be established between the sheet metal (or fabric) and the wing structure and fillet, which will effectually fasten the sheet metal where it passes under the fillets in such a way that 5 injury to any portion of the sheet will not extend beyond or affect the sheet beyond the two fillets next adjacent on either side of such injury, nor beyond the two ribs next adjacent to the injury. If desired, 10 the wing covering may be applied in smaller sheets, as additional joints may be placed under each tightening fillet. If such joints take the form of direct attachment, as by nailing or riveting, to the wing structure, the limitation of the effects of 15 injury to a single panel of the wing will be still more completely secured.

If it is found necessary after the straining fillets have been tightened the edges of 20 the metal sheets may be nailed to the ribs, adjacent sheets being made either to butt against one another or to overlap one another slightly, but it is quite possible that the powerful longitudinal tension of the 25 sheets and the frictional grip on the ribs or spars which will result therefrom will be sufficient to take the wind pressure without positive attachment of the sheets to the ribs. When the fillets are employed for securing 30 the sheet material in position, the means adopted for fastening the material prior to the final tensioning may be of a temporary character.

It is to be understood that the invention 35 is not to be confined to any particular construction or arrangement of wing frame

or other structure, nor to any particular number or shape of ribs, spars or other members forming the structure, nor to any particular material with which the structure 45 is to be covered.

Having now described our invention, what we claim as new and desire to secure by Letters Patent is:—

1. A method of securing and tensioning 50 relatively stiff but flexible sheet material upon aeroplane wing supporting structures having top and bottom grooves, which consists in first stretching the material around the structure and securing it in position, 55 placing fillets against the outer surface of the material at the points alined with the grooves, and finally passing a single tensioning device through both the fillets, material and supporting structure and simultaneously drawing the fillets into the grooves, 60 whereby both sides of the wing material will be simultaneously and equally tensioned.

2. An aeroplane wing including a spar 65 extending longitudinally of the wing and having top ad bottom grooves communicating through an aperture which extends entirely through the spar, relatively stiff but flexible sheet material forming the top and bottom of the wing, fillets engaging said 70 material and forcing the same into said grooves, and a single tensioning device extending through the fillets, material and spar aperture for simultaneously tensioning both sides of the material.

3. A structure as defined in claim 2 in which the sheet material is metal.

In testimony whereof we have signed our names to this specification.

WALTER ROSENHAIN.
SYDNEY L. ARCHBUTT.
